UNITED STATES PATENT OFFICE.

JAMES HARVEY STRONG, OF STEUBENVILLE, OHIO.

DESIGN FOR A REFLECTOR-SHADE.

42,403.

Specification for Design.

Patented Apr. 9, 1912.

Application filed November 3, 1911. Serial No. 658,447. Term of patent 7 years.

To all whom it may concern:

Be it known that I, JAMES HARVEY STRONG, a citizen of the United States of America, residing at Steubenville, in the State of Ohio, have invented a certain new, original, and ornamental Design for Reflector-Shades, of which the following is a specification.

In the drawing—Figure 1 is an elevation. Fig. 2 is a bottom plan of the shade.

The shade has on its surface longitudinally-extending, concave, substantially semi-circular flutes 1 arranged in pairs, the pairs

of flutes being separated by longitudinal, plain areas 2, and the flutes of each pair being separated by an angular prism 3.

I claim—

The ornamental design for a reflector shade as shown and described.

Signed by me at Steubenville Ohio this 1st day of November 1911.

JAMES HARVEY STRONG.
